CLAIM

The ornamental design for a tool handle for surface-preparation tool, as shown and described.

DESCRIPTION

FIG. 1 is a right and front side perspective view of a first embodiment of a tool handle for surface-preparation tool showing the new design, the left and right sides being mirror images of one another and the front and back sides being mirror images of one another;

FIG. 2 is a right side elevational view of the tool handle for surface-preparation tool of FIG. 1;

FIG. 3 is a front side view of the tool handle for surface-preparation tool of FIG. 1, the front and back sides being mirror images of one another;

FIG. 4 is a front end view of the tool handle for surface-preparation tool of FIG. 1;

FIG. 5 is rear end view of the tool handle for surface-preparation tool of FIG. 1;

FIG. 6 is a right and front side perspective view of a second embodiment of a tool handle for surface-preparation tool showing the new design, the left and right sides being mirror images of one another and the front and back sides being mirror images of one another;

FIG. 7 is a right side elevational view of the tool handle for surface-preparation tool of FIG. 6;

FIG. 8 is a front side view of the tool handle for surface-preparation tool of FIG. 6, the front and back sides being mirror images of one another;

FIG. 9 is a front end view of the tool handle for surface-preparation tool of FIG. 6; and,

FIG. 10 is rear end view of the tool handle for surface-preparation tool of FIG. 6.

The broken lines shown in the drawings are for the purpose of illustrating unclaimed portions of the tool handle for surface-preparation tool and form no part of the claimed design.
